Primary Examiner — Cynthia R Underwood

(57) **CLAIM**

The ornamental design for a clamp for tubes, hoses, pipes or cables including top, middle, base and connector portions, as shown and described.

DESCRIPTION

1. Clamp for tubes, hoses, pipes or cables including top, middle, base and connector portions

1.1 : Perspective

1.2 : Front, the back view being identical thereto

1.3 : Right, the left view being identical thereto

1.4 : Top

1.5 : Bottom

1.6 : Exploded

1.7: Perspective view of top portion shown separated from remainder of the clamp for tubes, hoses, pipes or cables including top, middle, base and connector portions.

1.8: Front view of top portion shown separated from remainder of the clamp for tubes, hoses, pipes or cables including top, middle, base and connector portions, the back view being identical thereto

1.9: Right view of top portion shown separated from remainder of the clamp for tubes, hoses, pipes or cables including top, middle, base and connector portions, the left view being identical thereto

1.10: Top view of top portion shown separated from remainder of the clamp for tubes, hoses, pipes or cables including top, middle, base and connector portions.

1.11: Bottom view of top portion shown separated from remainder of the clamp for tubes, hoses, pipes or cables including top, middle, base and connector portions.

1.12: Perspective view of middle portion shown separated from remainder of the clamp for tubes, hoses, pipes or cables including top, middle, base and connector portions.

1.13: Front view of middle portion shown separated from remainder of the clamp for tubes, hoses, pipes or cables including top, middle, base and connector portions, the back view being identical thereto

1.14: Right view of middle portion shown separated from remainder of the clamp for tubes, hoses, pipes or cables including top, middle, base and connector portions, the left view being identical thereto

1.15: Top view of middle portion shown separated from remainder of the clamp for tubes, hoses, pipes or cables including top, middle, base and connector portions.

1.16: Bottom view of middle portion shown separated from remainder of the clamp for tubes, hoses, pipes or cables including top, middle, base and connector portions.

1.17: Perspective view of base portion shown separated from remainder of the clamp for tubes, hoses, pipes or cables including top, middle, base and connector portions.

(Continued)

1.18: Front view of base portion shown separated from remainder of the clamp for tubes, hoses, pipes or cables including top, middle, base and connector portions, the back view being identical thereto

1.19: Right view of base portion shown separated from remainder of the clamp for tubes, hoses, pipes or cables including top, middle, base and connector portions, the left view being identical thereto

1.20: Top view of base portion shown separated from remainder of the clamp for tubes, hoses, pipes or cables including top, middle, base and connector portions.

1.21 : Bottom view of base portion shown separated from remainder of the clamp for tubes, hoses, pipes or cables including top, middle, base and connector portions.

1.22: Perspective view of connector portion shown separated from remainder of the clamp for tubes, hoses, pipes or cables including top, middle, base and connector portions.

1.23: Front view of connector portion shown separated from remainder of the clamp for tubes, hoses, pipes or cables including top, middle, base and connector portions, the back view being identical thereto

1.24: Right view of connector portion shown separated from remainder of the clamp for tubes, hoses, pipes or cables including top, middle, base and connector portions, the left view being identical thereto

1.25: Top view of connector portion shown separated from remainder of the clamp for tubes, hoses, pipes or cables including top, middle, base and connector portions.

1.26 : Bottom view of connector portion shown separated from remainder of the clamp for tubes, hoses, pipes or cables including top, middle, base and connector portions.

The broken lines represent portions of the structure that form no part of the claim.
